(57) **CLAIM**

The ornamental design for a RV screen door cross bar handle, as shown and described.

DESCRIPTION

FIG. 1 is a perspective view of a RV screen door cross bar handle showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded view thereof; and,

FIG. 9 is another perspective view thereof, showing the RV screen door cross bar handle is installed on the screen door. The broken lines depict environment only which form no part of the claimed design.
